UNITED STATES PATENT OFFICE.

JAMES MEIKLE, OF PROVIDENCE, RHODE ISLAND.

BLEACHING APPARATUS.

SPECIFICATION forming part of Letters Patent No. 338,096, dated March 16, 1886.

Application filed October 8, 1885. Serial No. 179,310. (No model.)

To all whom it may concern:

Be it known that I, JAMES MEIKLE, a subject of the Queen of Great Britain, but who has declared his intention of becoming a citizen of the United States, residing in Providence, in the county of Providence and State of Rhode Island, have invented certain new and useful Improvements in Bleaching Apparatus, of which the following is a specification.

10 My invention has reference to that class of apparatus required for cleansing and bleaching cotton and other textile fabrics.

The object of my invention is to provide improved apparatus whereby the cloth or other substance to be treated may be operated upon in a more thorough and effective manner than heretofore, whereby the result may be produced in a shorter time without injury to the fabric, and whereby larger quantities of goods 20 may be operated upon within the same area and with less shrinkage to the goods.

The essential features of the process of bleaching fabrics, as ordinarily conducted at the present time, consist, generally, in successive boilings and washings in solutions of lime, 25 in very dilute acid, in a solution of soda-ash, and in solutions of chlorine. During the intervals between these several treatments the fabric is washed many times in water, and a 30 period of not less than from four to eight days is necessarily occupied in carrying out the whole process. The object of the several different and successive treatments is to entirely remove from the fabric the oils and other extraneous substances which have become incorporated with it during the process of manufacture, and to enable the chlorine, which is 35 the principal bleaching agent, to exert full and equal chemical action upon all parts of 40 the fabric, so as to produce a uniform whiteness of the same in every part.

The essential feature of my invention consists in exposing the fabric to the action of the bleaching agent or solutions in such a manner 45 that the foreign substances are not only forced out of the fabric by mechanical action, but the bleaching liquid is brought into intimate, rapid, and effectual contact with every portion of it, thereby producing the desired effect 50 with great rapidity, and at the same time without injury to the fabric. This I effect,

mainly, by bringing the cloth or other material to be operated upon into such a position with reference to a series of pipes carrying the bleaching-liquid (in an inclosed keir or boiler) that the solution may be forced, under considerable pressure, entirely through the interstices of the fabric. Large quantities of the chemical solution are thus brought into contact with every portion of each one of the 60 threads of the fabric in a short period of time, thus rapidly producing both the cleansing and the bleaching effects.

In Letters Patent No. 311,349, issued to me January 27, 1885, I have described an apparatus for carrying out the process which I have described.

My present invention consists in certain additions to the apparatus described in said Letters Patent, by means of which I am enabled 70 to so treat the goods before they are carried into the inclosed keir that the whole process is very much shortened and nearly the full width of the goods is preserved.

In the ordinary process of bleaching, the cloth 7 is always considerably reduced in its width, so that a piece of goods woven, say, thirty-six inches wide, will not ordinarily measure over thirty-two or thirty-three inches after it is bleached. This is caused originally by the first wetting of the goods, and after that the straining of the piece lengthwise in carrying it through the machinery necessary for the bleaching process tends to lengthen the same, resulting in the above narrowing, which can 8 not afterwards be remedied to any considerable extent, but the goods remain permanently of less width than they were woven. By my improved process the cloth after bleaching remains nearly the same width as at first, as I provide for a slight, but continuous, stretching of the goods in the direction of their width after the first wetting and before they pass into the keir.

In the accompanying drawings, Figure 1 is an elevation, partly in section, showing apparatus embodying the essential features of my invention. Fig. 2 is a detail view of the rollers.

Similar letters denote like parts.

I have ascertained by experiment that in bleaching by my process it is wholly unneces-

sary in most cases to use successively several solutions, as in the ordinary process of bleaching. A single solution containing the necessary elements, both for cleansing and bleaching the fibers, has been found generally sufficient to produce the best results. Several pieces of cloth are taken at the same time, and these are well soaked in a tank containing the same liquid as it is intended to use throughout the process. The ends of the several pieces are then taken together and are drawn out of the tank over rollers in the usual manner. They are then made to pass through a second tank containing the same kind of liquid, and while passing through this tank the cloth is successively subjected to sprays or streams of the liquid, which is forced against it in a heated state through perforated pipes, suitably arranged for the purpose. The object of this is to more perfectly cleanse the fabric and to have it more thoroughly impregnated with the liquid, and also to have the oils and other extraneous substances more nearly dissolved and loosened before it enters into the keir. While being thus subjected to the spray of the liquid through perforated pipes in this tank, the cloth is passed successively between several pairs of fluted rollers, so arranged as to keep the cloth stretched out to its full width. As it leaves this tank it passes through a pair of nipping-rollers, and is then spread out and folded back and forth in the usual manner, in folds of a yard, or thereabout, in length, until a large number of thicknesses have been spread evenly together. I have found in practice that three hundred thicknesses or more may conveniently be laid together and can be successively operated upon by the solution, as applied in the next step of the process. These folds are laid upon an endless belt, and from this are carried through successive pairs of rollers to the inside of the keir, where the principal part of the operation of bleaching is accomplished. The keir is of sufficient length to admit of a number of series of folds or layers of cloth, as above described. The width of the keir is the same as the width of the cloth. Within the keir the series of folds are received upon an endless belt or apron, of wire-cloth or similar open construction, and are carried slowly through the keir in the direction of its length, passing out through a system of rollers similar to that at its entrance. Within the keir and just above the layers of cloth a system of perforated pipes is arranged, the pipes being placed side by side, extending lengthwise of the keir and covering its entire breadth. These pipes have numerous perforations in their under sides, and are intended to convey the bleaching solution and to discharge the same forcibly through the perforations and downward upon the layers of cloth over the whole extent as spread out within the keir. The mass of folded cloth rests upon the endless apron before mentioned, beneath

which is a perforated false bottom of the keir a few inches above the main bottom. Underneath this false-bottom the solution collects 70 after having been forced through the mass of cloth, from which it is pumped back into the same tank that supplies it to the perforated pipes above the cloth. In this way the same solution can be used over and over again until its strength is exhausted, when it may be drawn away from the bottom of the keir and a new supply provided. 75

The two most important features of my invention consist in first applying the solution 80 to the cloth by means of the perforated showering-pipes, as before explained, in the tank before it enters the keir, whereby it is prepared for the process within the keir, and in the second application of the liquid by the 85 pipes within the keir, which applies it in a finely-divided state and under sufficient pressure to force the liquid through the entire mass of cloth and over its whole surface in so effectual and rapid a manner as to both cleanse and 90 bleach the cloth in a short time.

In some cases, without my present improvements, it might be necessary to pass the cloth in the same manner through a similar keir with a fresh solution and under less pressure 95 than in the first one; but this will probably never be the case under the improved process.

After leaving the keir the fabric is thoroughly washed in clear water, after which it 100 may be soaked in chlorine liquor. Then it should be soured and washed in clear water, and then dried.

Referring now to the accompanying drawings, A represents a tank in which the cloth 105 C is first soaked, the tank being partly filled with a solution containing the bleaching and cleansing agents. From the tank A the several ends of the cloth are passed over the roller B into the tank A'. This tank is also partly 110 filled with a similar solution. It passes down into the tank and under the roller E, thence up and between the rollers F, then under the roller E', again between the rollers F', and so on under and between the successive similar 115 rollers until it passes out of the tank between the rollers E².

At a convenient distance above the tank A' is situated the tank A². This tank contains the same kind of solution as the tanks previously mentioned, and is kept in a heated condition by steam, which enters through the pipe S, being admitted to the tank by the valves and to the system of pipes by the valve s'. From the tank A² the pipe S² supplies the 125 branch S⁴, the latter extending along one side of the tank A', on the inside and in position about midway between the systems of rollers E and F, and terminating in the horizontal pipes s⁵, the length of which is equal to the 130 width of the tank and of the cloth, and which extend across the tank in the path of the fabric as it moves. These are perforated in such a manner that as the cloth passes downward

and upward under and between the successive rollers, as described, it receives the solution forced upon it in the shape of fine streams or spray, and it also dips into the solution every time that it passes under the rollers E E'. These pipes are, moreover, so situated that the several pieces of cloth are carried some on one side and some on the other of the pipes, as shown in the figure. As many of the pipes as may be necessary can thus be used, depending upon the number of pieces of cloth operated upon, so that the number of pieces operated upon by each pipe shall be such as will receive the full effect of the solution. The result is that when the cloth leaves this tank it has been thoroughly penetrated by the solution, and the oils and other extraneous substances have become nearly dissolved and loosened from the fabric. Each of the pairs of rollers F F' have their surfaces fluted, and are arranged so that the elevations upon the surface of one roller fit into the depressions upon the surface of the other. (See Fig. 2.) By this means the fabric is kept by a gentle strain to its full width, and the shrinking effect of the first wetting in the tank A is overcome, so that when the cloth leaves the tank A' through the last pair of rollers F', which are smooth on their surfaces, it is nearly of the same width as before it was placed in the tank A. After that the cloth shrinks but very little. The advantage gained by this device in this connection is that the shrinkage caused by the first soaking is immediately counteracted.

The rollers F' press the several pieces of cloth closely together, and it is then carried onto the upper side of the endless belt or apron G, which moves in the direction of the arrow over the rollers G' G'. On this belt the cloth is folded back and forth in folds of about one yard evenly and smoothly, until a sufficient number of thicknesses have been made to be properly operated upon within the keir. From the endless belt G the cloth thus folded is led between two pairs of closely-fitting rollers, H and H'. These rollers are pressed together by suitable springs, and have their bearings within the sides of the box X. This box is securely attached to the end of the keir K. Through an opening, k, in the end of the keir, the cloth, having its layers pressed closely together, enters the keir, and the series of folds are laid successively upon the endless belt L, which passes in the direction of the arrow over the rollers l l. This belt is preferably made of wire or other woven material, so as to be as open as possible and not obstruct the passage of the solution downward as it is forced through the cloth. The width of the keir is the same as the width of the cloth, so that the folds of the latter fit as closely as practicable the sides of the former. The cloth having passed through the keir leaves the same through a similar opening, k', and passes between the rollers H' and H".

Within the keir, and extending throughout

its length in a position just over the layers of cloth, is a system of pipes, P. These are placed closely side by side throughout the width of the keir, and are each joined to the cross-pipe P'. Into this is led the supply-pipe P² from the tank O, which tank contains the bleaching solution. The solution in the tank is heated by the steam-pipe s². The valve s³ admits the solution from the tank O to the pipe P'. A pressure of from sixty to one hundred pounds per square inch is preferably maintained within the tank O and is communicated to the supply-pipe P. As the cloth passes through the keir on the endless belt L the solution is admitted to the system of pipes P by turning the valve s⁴, and under the pressure above stated the solution is driven through the perforations which closely cover the under surface of the pipes P, is showered upon and forced through the layers of cloth spread out evenly beneath and fitting the sides of the keir closely. The solution, having passed through the cloth and through the wire belt L, passes also through the perforated false bottom K' and falls to the bottom of the keir. The pipe P³ leads from the bottom of the keir into the tank O, and the pump U within said pipe is kept in action to remove the solution from the bottom of the keir into the tank O. It is evident that by this means a rapid circulation of the solution may be kept up as long as the latter is fit to use. When the solution is exhausted, it may be drawn off by means of pipe P⁴ below the keir, and new solution may be let into the tank O by means of the pipe P⁵. The required circulation of liquids between the tanks A' and A² is kept up in the same manner by means of the pump V' and pipe S⁶, and it may be finally drawn off by the pipe S⁷. After the cloth has left the keir it is led into the tank R, in which it is thoroughly washed. It may then be soaked in a solution of chlorine to further whiten it, then soured, washed, and dried in the ordinary manner. It is not necessary that there shall be two tanks, A² and O, as described, as a single tank can be used, from which both the pipe S² and P² may be supplied; but it is preferable to use two, for the reason that the solution in the tank O can thus be kept cleaner and in better condition for the final process as carried on within the keir. A great part of the oil and other substances is washed from the fabric in its passage through the tank A', and the solution in this tank therefore becomes soiled and requires renewal oftener than in the tank O. By keeping them separate, therefore, it will be seen that the process is more perfect in its effects and less time is consumed in the operation of bleaching within the keir.

I have found in practice that by means of the additional improvements in the apparatus as herein described I can shorten the time occupied for bleaching considerably as compared with the time occupied by the process without them. Larger quantities of cloth can be oper-

ated within the same time, and when the cloth is finished it has nearly the same width as when it came from the loom.

I do not limit myself to the number of series 5 of rollers in the tank A' shown in the drawings. Two or three series may be sufficient for ordinary purposes, but more can be used in case the fabric requires the application of greater quantities of the solution to properly 10 prepare it for going into the keir.

I claim as my invention—

1. The combination, substantially as hereinbefore set forth, in a bleaching apparatus, of a tank for holding the bleaching solution and 15 having a series of fluted or corrugated rollers whereby the fabric is kept extended to its full width while passing through said tank, and a bleaching keir or boiler containing an endless belt or apron within the same for conveying 20 the fabric, a system of perforated pipes extending above said belt or apron, and means,

substantially such as described, for conveying the fabric into and out of said keir.

2. The combination, substantially as hereinbefore set forth, with a tank, A', of the series 25 of rollers E, F, E', and F', and the system of perforated pipes S⁵.

3. The combination, substantially as hereinbefore set forth, of a tank A', the series of rollers E E', the corrugated rollers F F', the 30 perforated pipes S⁵, with the keir or boiler K, containing the belt L, perforated pipes P, and the means, substantially such as described, for conveying the fabric through the tank A' and the keir K.

In testimony whereof I have hereunto subscribed my name this 24th day of September, A. D. 1885.

JAMES MEIKLE.
